UNITED STATES PATENT OFFICE

EARL J. LEAP, OF MADLEY, PENNSYLVANIA

STONE CRUSHER

Application filed April 2, 1931. Serial No. 527,259.

This invention relates to a machine adapted to crush stone or similar material and it aims to provide a construction which may be operated at exceedingly low cost and in which the material is squeezed rather than rubbed in order to effect the crushing.

It is also aimed to provide a novel construction which is exceedingly compact, adjustable according to the degree of crushing desired and a construction which provides minimum moving joints.

The more specific objects and advantages will become apparent from a consideration of the description following taken in connection with accompanying drawings illustrating an operative embodiment.

In said drawings:—

Figure 1 is a view of the crusher in central vertical section,

Figure 2 is a sectional view taken on the line 2—2 of Figure 1,

Figure 3 is a sectional view taken on the line 3—3 of Figure 1,

Figure 4 is a sectional view taken on the line 4—4 of Figure 1, and

Figure 5 is a sectional detail of the bearings for the drive shaft and eccentric.

Referring specifically to the drawings, 10 generally designates a boxing which is open at the top to receive the material to be crushed and open at the bottom for discharge thereof. Such boxing is generally of rectangular form and exceedingly sturdy and solid.

15 A movable or crushing jaw is employed at 11 which is in the form of a lever pivoted on a cross shaft 12 mounted in suitable arbors or plates 13 removably bolted or otherwise secured to the boxing. The openings 12' in arbors 13 which mount said shaft 13, are eccentric. Since the arbors are removable, they may be reversed so that the openings 12' may be arranged closer to the rear of the machine than to the front. In this way, the

20 extent of the mouth of the crusher may be regulated. To secure the regulation, the arbors are removed, and then turned end for end. The particular adjustment which results from the construction shown, by the

shown in Figure 1 to the other position, results in opening up the mouth of the crusher double the extent shown. The jaw 11 carries a wear plate 14 of hardened metal, at its crushing surface between which and a stationary wear plate 15, also of hardened metal, the material to be crushed, is received. The material-receiving space is closed at the sides by cheeks or plates 16, of material similar to the parts 14 and 15.

The jaw 11 is thickened at the lower end and at the rear thereof carries a bar 17 of hardened metal, removably secured in place between flanges 18 by any suitable number of bolts 19. A jaw actuator member is shown at 20 in which an eccentric portion 21, of a shaft 22 is loosely mounted, the same having roller bearing or other anti-friction engagement as at 23 with the actuator. Such actuator has a plurality of grooves or slots 24 around the same in any one of which a contact bar 25 may be fastened by any suitable number of bolts 26 passing through openings 27 therein.

Attention is called to the fact that the base 75 of each groove 24 is at a different distance from the axis of the eccentric 21 and hence in the contact bar 25 is secured in different grooves or slots 24, it will project different distances beyond the exterior of the actuator 80 and thus will operate the jaw 11 to different extents, according to the fineness or degree of crushing desired for the material.

The bolts 19 and 26 are applied loosely in the openings in the jaw 11 and actuator 85 member 20. Such jaw and members are cut away to provide recesses accommodating a pair of nuts 19' and 26' on the bolts 19 and 26, respectively. As a result of this construction, one of the nuts 19' and 26' will serve to 90 secure the bolts 19 and 26, respectively in locked position while the coacting nut will serve as a lock therefor.

The shaft 22 may have a fly-wheel 28 thereon and it may be driven from any suitable 95 source of power applied to a pulley, by way of example, as shown at 29.

A relatively strong contractile spring 30 is connected at 31 to the jaw 11 and at 32 to a portion of the boxing.

As a result of the construction described, the rock disposed between the plates 14 and 15 will be crushed since the eccentric 21 moves the actuator 20 toward and away from the jaw 11, and since the latter is urged in one direction by the coil spring 30 and moved in the opposite direction against the tension of that spring through the engagement of the contact bar 25 and bar 17. The contact bar 25 preferably has a rounded nose at 33 which is engaged in a socket 34 of the bar 17.

Various changes may be resorted to provided they fall within the spirit and scope of the invention.

I claim as my invention:—

- 15 1. In a crusher, a jaw movable to crush material, an actuator for said jaw, a shaft having an eccentric operable through the actuator to move the latter to cause movement of the jaw, a contractile spring urging movement of the jaw counter to said actuator, said actuator being rotatable on the eccentric for adjustment thereof and having means controlled by the adjustment for moving the jaw 25 to different extents to govern the degree of crushing.
- 20 2. In a crusher, a jaw movable to crush material, an actuator for said jaw, a shaft having an eccentric operable through the actuator to move the latter to cause movement of the jaw, a contractile spring urging movement of the jaw counter to said actuator, said actuator having a plurality of slots about the same of different depths, a contact bar 30 applicable selectively to said slots and adapted for engagement with the jaw, said actuator being rotatable about said eccentric to operatively position the slots.
- 25 3. In a crusher, a jaw movable to crush material, means to actuate the jaw, a shaft pivotally mounting the jaw, arbors having openings providing bearings for said shaft, said arbors being removable and reversible, and the openings of said arbors for said shaft 35 being closer to one end than to the other.
- 40 4. In a crusher, a jaw movable to crush material, actuating means for said jaw, a shaft pivotally mounting the jaw, a pair of relatively oblong arbors having openings for removably mounting said shaft, said arbors 45 being removable and reversible end for end, and the openings of said arbors mounting said shaft being located closer to one end of each arbor than to the other, to enable adjustment 50 of the mouth of the jaw according to the position of the arbors.
- 55 5. In a crusher, a jaw movable to crush material, actuating means for said jaw, a shaft pivotally mounting the jaw, a pair of relatively oblong arbors having openings for removably mounting said shaft, said arbors being removable and reversible end for end, and the openings of said arbors mounting said shaft being located closer to one end of each arbor than to the other, to enable adjustment 60 of the mouth of the jaw according to the position of the arbors.

In testimony whereof I affix my signature.
EARL J. LEAP.
